CLAIM

The ornamental design for an electric grinder, as shown and described.

DESCRIPTION

FIG. 1 is a front, top perspective view of a first embodiment of an electric grinder, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a rear, bottom perspective view of a second embodiment of the electric grinder;

FIG. 10 is a front, top perspective view of a third embodiment of the electric grinder;

FIG. 11 is a rear, bottom perspective view thereof;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof;

FIG. 17 is a bottom plan view thereof;

FIG. 18 is a rear, bottom perspective view of a fourth embodiment of the electric grinder;

FIG. 19 is a front, top perspective view of a fifth embodiment of the electric grinder;

FIG. 20 is a rear, bottom perspective view thereof;

FIG. 21 is a front elevation view thereof;

FIG. 22 is a rear elevation view thereof;

FIG. 23 is a left side elevation view thereof;

FIG. 24 is a right side elevation view thereof;

FIG. 25 is a top plan view thereof;

FIG. 26 is a bottom plan view thereof; and,

FIG. 27 is a rear, bottom perspective view of a sixth embodiment of the electric grinder.

The broken lines in the figures illustrate portions of the article that form no part of the claimed design.
